US0D1109217S

(12) **United States Design Patent** (10) **Patent No.:** **US D1,109,217 S**
(45) **Date of Patent:** **** Jan. 13, 2026**

(54) **ACTION CAMERA**

(71) Applicant: **ARASHI VISION INC.**, Shenzhen (CN)

(72) Inventors: **Limin Ma**, Guangdong (CN); **Jingkang Liu**, Guangdong (CN); **Fei Gao**, Guangdong (CN)

(73) Assignee: **ARASHI VISION INC.**, Shenzhen (CN)

(**) Term: **15 Years**

(21) Appl. No.: **35/521,571**

(22) Filed: **May 20, 2024**

(80) **Hague Agreement Data**

Int. Filing Date: **May 20, 2024**
Int. Reg. No.: **DM/238135**
Int. Reg. Date: **May 20, 2024**
Int. Reg. Pub. Date: **Jul. 5, 2024**

(30) **Foreign Application Priority Data**

Nov. 20, 2023 (CN) 202330759305.0
(51) LOC (15) Cl. **16-06**
(52) U.S. Cl.
USPC **D16/218**
